ALBERT L. HARVEY, OF BRADDOCK TOWNSHIP, ALLEGHENY COUNTY, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

1,390,552.

Specification of Letters Patent. Patented Sept. 13, 1921.

Application filed November 7, 1917. Serial No. 200,661.

To all whom it may concern:

Be it known that I, ALBERT L. HARVEY, a citizen of the United States, and a resident of Braddock township, in the county of Allegheny and State of Pennsylvania, have invented a new and useful Improvement in Motor-Control Systems, of which the following is a specification.

My invention relates to systems of control 10 and particularly to systems of control for governing the operation of fluid systems.

One object of my invention is to provide a system of control of the above-indicated character that shall govern the operation of 15 a plurality of motor-operated pumps in accordance with operating conditions of a fluid system.

In fluid systems now in service for use 20 in rolling mills and other industrial properties, it is desirable to have the pressure in the fluid systems maintained substantially constant and, in many cases, it is very desirable to severally and jointly control the 25 operation of a plurality of motor-operated pumps in each of the fluid systems. In some systems, it may only be necessary to vary the operation of a single motor-operated pump, whereas, in other systems, it may be necessary to simultaneously vary the 30 operation of a number of motor-operated pumps in order to maintain the pressure in the system substantially constant.

In a system constructed in accordance 35 with my invention, a fluid system is provided with a plurality of motor-operated pumps which may be severally and jointly controlled, either manually or automatically in accordance with the pressure in the fluid system.

40 In the accompanying drawing, the single figure is a diagrammatic view of a control system constructed in accordance with my invention.

Referring to the drawing, a fluid system 45 1 is provided with three or more pumping stations, three only of which, 2, 3 and 4, are illustrated, for maintaining pressure in the fluid system. Each of the pumping stations is connected to a supply circuit embodying 50 supply conductors 5 and 6 and to two control conductors 7 and 8 which are directly connected to a fluid-controlled device 9 for a purpose to be set forth hereinafter.

The pumping station 2 embodies a pump

10, which is directly connected to the fluid 55 system 1, and a motor 11, embodying an armature 12 and a shunt field winding 13, which is connected to the pump 10. A rheostat 14, embodying a contact arm 15 coöperating with a resistor 16 and controlled by a 60 pilot motor 17, is adapted to control the energization of the shunt field winding 13. The pilot motor 17 embodies an armature 18 and two field windings 19 and 20, which are wound in opposite directions in order to 65 rotate the motor in opposite directions when severally energized.

A two-pole, double-throw switch 21 is provided for preparing the pumping station for operation, either automatically in accordance with the pressure in the fluid system or manually, at will. The switch 21 embodies two contact members 22, which are adapted to bridge contact terminals 23 and 25, and 24 and 26 when in the upper or automatic position and to bridge contact terminals 25 and 27, and 26 and 28 when in the lower or manual position. The contact terminals 24 and 23 are respectively connected to the control conductors 7 and 8, and the 70 contact terminals 25 and 26 are respectively connected to the field windings 19 and 20 of the pilot motor 17. A single-pole, double-throw switch 29 embodies a movable contact member 30, which is adapted to bridge 75 either the contact terminals 31 and 32 or the contact terminals 32 and 33. The switch 29 is provided for controlling the direction of rotation of the pilot motor 17 when the switch 21 is set for manual operation. 90

The fluid-controlled device 9, which is connected to the control wires 7 and 8, is adapted to control the various pumping stations in accordance with the pressure in the fluid system 1. The fluid-operated device 9 95 embodies a contact arm 34 which is pivoted, intermediate its ends, to a support 35 and is provided with two contact members 36 and 37 which are respectively adapted to engage contact terminals 38 and 39 when the arm 34 is moved to its extreme positions. A plunger 40, which operates within a cylinder 41, is connected to the contact arm 34 near one end thereof, and a compression spring 42 is connected to the contact arm 100 105 near the other end thereof. The cylinder 41 is connected to the fluid system 1 and is adapted to operate the plunger 40 and the

contact arm 34 in accordance with the pressure in the fluid system.

The pumping stations 3 and 4 may be similar in construction and in operation to 5 the pumping station 2 and, accordingly, a detailed illustration and description thereof is deemed unnecessary. In the pumping station 3, however, a drum controller 43 is substituted for the manually operated switches 10 21 and 29 which are illustrated in the pumping station 2. In position *a* of the drum controller 43, the pilot motor is connected to the control lines 7 and 8 in order to be automatically governed in accordance with the 15 pressure in the fluid system 1. In positions *b* and *c* of the controller 43, the pilot motor is respectively connected for operation in a forward and in a reverse direction.

Assuming the switch 21 of the station 2 20 to be closed in its upper position, in order to govern the operation of the motor-governed pump 10 in accordance with the pressure in the fluid system 1, and the switches in the stations 3 and 4 to be similarly connected if it is desired to operate the pumps 25 associated therewith in accordance with the pressure in the fluid system, the system will be automatically controlled by the pressure in the system 1. If the pressure in the fluid 30 system 1 is reduced below a predetermined point, the spring 42, acting in opposition to the fluid pressure in the cylinder 41, will give the contact arm 34 a movement of rotation such as to connect the contact terminals 37 and 39. Thus, a circuit is completed from the negative supply conductor 6 through the contact terminals 37 and 39, control wire 8, contact terminals 23 and 25— 35 which are bridged by one of the contact members 22—field winding 19 and the armature 18 to the positive supply conductor 5. The pilot motor 17 is operated in a clockwise direction to increase the resistance value of the resistor 16 which is included in circuit 40 with the shunt field winding 13 and thus increase the speed of the motor-driven pump 10. When the pressure in the fluid system is raised to normal, the plunger 40 is operated to break the connection between the 45 contact terminals 37 and 39.

When the pressure in the fluid system is raised somewhat above normal pressure, the arm 34 is operated by the plunger 40 to connect the contact terminals 36 and 38 and complete a circuit through the field winding 20 of the pilot motor 17. The circuit through the pilot motor is traced from the negative supply conductor 6, through contact terminals 36 and 38, control wire 7, contact terminals 24 and 26—which are bridged by one of the contact members 22—field winding 20 and the armature 18, to the positive supply conductor 5. The pilot motor 17 is now operated in a counter-clockwise direction to reduce the resistance in-

cluded in circuit with the shunt field winding 13 and thus reduce the speed of the motor-operated pump 10. In setting forth the operation of the pumping station 2, it is to be understood that any of the other 70 pumping stations may be jointly controlled in a similar manner by the fluid operated device 9. It is also to be understood that the rheostat 14 may be provided with the customary limit switches for preventing over-travel of the contact arm 15 which, for example, are illustrated in a companion application of mine, Serial No. 200,662, filed 75 Nov. 7, 1917.

In case it is desired to manually control 80 the operation of the pump 10, the switch 21 is closed in its lower position, and the speed of the pump is controlled solely by means of the switch 29. When it is desired to increase the speed of the motor 10, the switch 85 29 is closed in its lower position and a circuit is completed from the negative supply conductor 6, through contact terminals 32 and 33—which are bridged by the contact member 30—contact terminals 25 and 27— 90 which are bridged by one of the contact members 22—field winding 19 and the armature 18, to the positive supply conductor 5. The pilot motor 17 and the contact arm 15 are rotated in a clockwise direction to increase the resistance included in circuit with the shunt field winding 13 and thus operate the motor 11 and the pump 10 at an increased speed. 95

In case it is desired to reduce the speed 100 of the motor 10, the switch 29 is closed in its upper position and a circuit is completed from the negative supply conductor 6 through contact terminals 31 and 32— 105 which are bridged by the contact member 30—field winding 20 and the armature 18 to the positive supply conductor 5. The pilot motor 17 and the contact arm 15 are rotated in a counter-clockwise direction to decrease the amount of resistance included 110 in circuit with the shunt field winding 13 and thus reduce the speed of the motor 11 and the pump 10. 115

Although I have described my invention in combination with a fluid system, it is to be understood that the same may be utilized for operating motor-operated gate valves, regulators, fans and any other similar devices.

Modifications in the system and arrangement and location of parts may be made within the spirit and scope of my invention, and such modifications are intended to be covered by the appended claims.

I claim as my invention:

1. In a system of control for a fluid system, the combination with a plurality of fluid pumps for maintaining pressure in the fluid system, a plurality of motors severally connected to said pumps, rheostats for gov- 125 130

- erning the excitation of said motors, and pilot motors for respectively controlling the operation of said rheostats, of a supply circuit, and means for jointly connecting any 5 number of said pilot motors to the supply circuit and controlling the operation thereof in accordance with the pressure in the fluid system.
2. In a system of control for a fluid system, the combination with a plurality of pumps and a plurality of motors for maintaining pressure in the fluid system, rheostats associated with the motor field windings, and pilot motors for respectively controlling the operation of said rheostats, of means for automatically controlling from a distant point the operation of said pilot motors in a forward and in a reverse direction in accordance with the pressure in the 10 fluid system.
3. In a fluid control system, the combination with a fluid pressure system, means comprising a plurality of main motors hav-
- ing armatures and field windings for maintaining pressure in the fluid system, a plurality of rheostats, and pilot motors for respectively controlling said rheostats to govern the excitation of said main motors, of automatic means controlled in accordance with the pressure in said fluid system for 25 governing the operation of said pilot motors from a distant point.
4. In a fluid control system, the combination with a fluid system, means comprising a plurality of main motors for maintaining 30 pressure in said fluid system, and a plurality of rheostats and of pilot motors for controlling the energization of said motors, of means controlled by the pressure in said fluid system for simultaneously governing 35 the operation of said pilot motors in a forward and in a reverse direction.

In testimony whereof, I have hereunto subscribed my name this 24th day of Oct., 1917.

ALBERT L. HARVEY.
